UNITED STATES PATENT OFFICE.

IRA J. HOLLENSBE, OF GREENSBURG, INDIANA.

WATER-COOLING APPARATUS.

1,010,495.

Specification of Letters Patent.

Patented Dec. 5, 1911.

Application filed March 27, 1911. Serial No. 617,311.

To all whom it may concern:

Be it known that I, IRA J. HOLLENSBE, a citizen of the United States, residing at Greensburg, in the county of Decatur and State of Indiana, have invented certain new and useful Improvements in Water-Cooling Apparatus, of which the following is a specification.

This invention relates to water cooling apparatuses for cooling water supplied to the water-jackets of internal combustion engines, and the object of the invention is to provide an apparatus of the above character which can be easily knocked down, taken apart when it is desired to clean and repair same, and can then be readily re-assembled.

A further object of the invention consists in the provision of a water cooling apparatus of the above character wherein the incoming hot water is so thoroughly distributed through the many peculiarly shaped pipes that the correspondingly shaped columns of water within said pipes enables the air to extract the greatest amount of heat therefrom in the shortest period of time.

I accomplish the objects of the invention by means of the apparatus shown in the accompanying drawings, forming a part hereof, in which—

Figure 1 is a front elevation of one-half of my water cooling apparatus, showing the upper and lower sections removed or disconnected from the central section, previous to the assembling of the several sections. Fig. 2 is a fragmentary detail vertical sectional view, on an enlarged scale, of the upper and lower sections of the apparatus, the central section thereof being broken away.

Referring to the drawings, the water cooling apparatus, herein shown as used in connection with an internal combustion engine for automobile service, contemplates the use of an intermediate or central section, a base section and a top section, all of which are secured together to form an operative unit structure.

The central section of the apparatus comprises an upper manifold plate 10, a lower manifold plate 11 and the side uprights 12, the latter securing the plates 10 and 11 together, and the plates and uprights forming the skeleton structure of said section. The plates 10 and 11 provide means for anchoring the vertically disposed tubes 15 which form passageways for the water from the

upper to the lower sections of the apparatus. The plates 10 and 11 have their side edges bent at right angles to form the projecting ribs 16 and 17 (see Fig. 2) and the metal is then given a reverse bend back against the faces of the ribs so as to double or reinforce and strengthen said ribs, besides adding rigidity to the plates. The reinforcement of the ribs provides edges of sufficient thickness to give good bearing upon the gaskets in the upper and lower sections of the apparatus to seal the joints between said sections, the latter construction being hereinafter more particularly described.

The upper section of the apparatus comprises an open bottom box like structure having a top 25, sides 26 and ends 27. This structure fits over the upper end of the central section and overlaps the projecting ribs 16 and 17 and is provided on its inner surface near the lower edge with the plate 30, as shown, to form the channel 31 adapted to receive and form a seat for the gasket 33 against which the rib 16 on the plate 10 bears. The upper section receives the water direct from the jackets of the engines through a suitable pipe 34. The water passes from the upper section through the pipes or tubes 15 to the lower section during which time the largest amount of heat is extracted from the water on account of the rectangular formation of the tubes 15 in cross section, the closeness of the side walls to each other producing thin columns of water for allowing a maximum radiation to take place. This construction enables the heat to be readily extracted from the thin columns of water.

The lower section of the apparatus consists of an open top rectangular box-shaped structure comprising the bottom 37, sides 38 and ends 39. This section fits over the lower end of the central section and overlaps the projecting rib 17 on the plate 11. The lower section is also provided on its inner surface near the upper edge with a plate 40, similar to the plate 30, and is bent to form the channel 41 adapted to form a seat for the gasket 42. The channel 41 extends entirely around the lower section enabling the rib 17 on the central section to bear against the gasket 42 in order to seal the joint between the two sections when they occupy an assembled position.

To hold the several sections of the apparatus together in operative position, I provide the tie-bars 50, consisting of a plurality

of flat bars of a size to conveniently pass through the tubes 15. The bars 50 are projected vertically and are located at convenient points within the apparatus. The bars 5 are provided at their upper ends with the hooks 51 adapted to engage suitable brace-bars 52 arranged horizontally within the upper section of the apparatus. The lower ends of the bars are each provided with an 10 aperture 53 adapted to receive the hooked ends of the screw-bolts 55, the latter extending downwardly through suitable guide-bars 56 arranged within and secured to the lower section of the apparatus. The screw-bolts 15 extend through the bottom 37 of the lower section and are provided with the nuts 58 so that a tension may be applied to hold the several parts of the apparatus together. The lower section is also provided 20 with the outlet pipe 60 through which the water passes from the apparatus to the water-jackets of the engines.

Having thus fully described my said invention, what I desire to secure by Letters 25 Patent, is—

1. A water cooling apparatus of the above specified class comprising a plurality of independent interlocking and communicating sections, an annular groove formed in each 30 of the upper and lower sections of the apparatus adapted to receive the edge of the adjacent section, means lying within said grooves to seal the joints between the sections when assembled, tie-means extending from the upper section of the apparatus to the lower section and adapted to draw all

sections together into operative relation, means arranged within the upper and lower sections for anchoring the ends of the tie-means, and tubes communicating with the 40 apparatus to form a water inlet and an outlet therefor.

2. A water cooling apparatus of the above specified class comprising a plurality of independent interlocking and communicating 45 upper, central and lower sections, the central section including a top and base plate, ribs formed along the edges of said plates, an upper section provided with an annular groove adapted to receive the rib on the adjacent edge of the central section, a lower section provided with an annular groove adapted to receive the rib on the adjacent edge of the central section, tubes arranged within the central section and communicat- 50 ing with the upper and lower section, tie-bars extending from the upper to the lower section, means arranged within the upper section for securing the upper ends of the bars, means arranged to secure the lower 55 ends of the bars, and tubes communicating with the apparatus to form a water inlet and an outlet therefor.

In witness whereof, I have hereunto set my hand and seal at Indianapolis, Indiana, 65 this first day of March, A. D. one thousand nine hundred and eleven.

IRA J. HOLLENSBE. [L. S.]
